UNITED STATES PATENT OFFICE.

FRANK BAILEY, OF NEW YORK, N. Y.

DESIGN FOR A CLASP FOR PACKAGE-FASTENERS.

SPECIFICATION forming part of Design No. 34,263, dated March 26, 1901.

Application filed February 15, 1901. Serial No. 47,518. Term of patent 7 years.

To all whom it may concern:

Be it known that I, FRANK BAILEY, a citizen of the United States, and a resident of New York, county of New York, and State of New York, have invented and produced a new and original Design for a Clasp for Package-Fasteners, of which the following is a specification, reference being had to the accompanying drawings, forming part thereof, in which—

Figure 1 is a plan view, and Fig. 2 a side view, of my newly-designed fastening device.

The leading or material feature of my design consists of the form of clasp for a package-fastener, which is composed of strong spring-wire bent at one end to form a loop *a*, and at the opposite end to form a spiral coil *b*, in which the second coil *b*² is higher than the bottom coil at one side and depressed at the opposite side substantially even with the bot-

tom coil, as shown at *b*³, the side *b*³ of the second coil being closely adjacent to and fitting within the corresponding side of the bottom coil and the said second coil and bottom coil being connected between the side *b*³ of the second coil and the shank *c* of the fastening device by means of a clamp *d*.

Having fully described my invention, what I claim as new, and desire to secure by Letters Patent, is—

The design for a clasp for package-fasteners, herein shown and described.

In testimony that I claim the foregoing as my invention I have signed my name, in presence of the subscribing witnesses, this 14th day of February, 1901.

FRANK BAILEY.
